SLIDING SHELF FOR REFRIGERATOR CABINETS

James L. Knight, Erie, Pa., assignor to General Electric Company, a corporation of New York

Application December 9, 1936, Serial No. 114,990

2 Claims. (Cl. 211—143)

My invention relates to refrigerator cabinets and more particularly to sliding shelves therefor.

It is an object of my invention to provide an improved arrangement for supporting sliding shelves in a compartment of a refrigerator cabinet.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a fragmentary perspective view of the lower portion of a refrigerator cabinet having a compartment provided with an arrangement for supporting sliding shelves therein embodying my invention; Fig. 2 is an enlarged side elevation of one of the supporting brackets employed in the arrangement of Fig. 1; and Fig. 3 is a side elevation of a modified form of the shelf supporting bracket.

Referring to the drawing, I have shown in Fig. 1 the lower portion of a refrigerator cabinet designed for household use provided with a metal outer wall 10 having a rectangular door opening 11 in the front wall thereof. A sheet metal inner liner 12 arranged in spaced relation within the outer wall 10 forms a food storage compartment 13 in the refrigerator cabinet. Preferably, the surface of the inner liner 12 presented to the food storage compartment 13 is covered with a vitreous enamel to provide smooth easily cleaned interior walls. The front wall of the metal inner liner 12 is provided with a rectangular door opening 14 which registers with the somewhat larger door opening 11 in the metal outer wall 10, the adjacent edges thereof being secured together by a strip of non-hydroscopic heat insulating material 15. Suitable heat insulating material 16 is arranged in the space between the metal outer wall 10 and the metal inner liner 12. The refrigerator cabinet is supported upon a series of sheet metal legs 17. The food storage compartment 13 is bounded by a plurality of interior walls including a rear wall 18, oppositely disposed side walls 19, and a suitable heat insulated door may be supported by hinges arranged at any side of the door opening formed in the front wall of the food storage compartment.

A removable shelf 20 is slidably supported in the food storage compartment 13 by a plurality of aligned shelf supporting brackets 21 secured

to each of the oppositely disposed side walls 19 of the food storage compartment 13. The shelf 20 includes a substantially rectangular border frame having front, rear, and sides 22, 23 and 24, respectively. A supporting surface is provided on the shelf 20 by a plurality of spaced flat bars 25 rigidly secured by welding, soldering or the like, to the front 22 and rear 23 of the border frame. These bars 25 are secured to the undersides of the front and rear portions of the border frame, so that the border frame constitutes a marginal stop about the periphery of the supporting surface of the shelf. A plurality of inverted U-shaped bars 26 are secured to the rear 23 of the border frame to afford additional marginal stops at the rear of the shelf.

Each of the brackets 21, as best shown in Fig. 2, is provided with a guide slot 27 therein for slidably receiving a side 24 of the border frame of the shelf 20 and is turnably secured to one of the oppositely disposed side walls 19 of the food storage compartment 13 by a screw 28 threaded into an aperture 29 formed in the side wall. These brackets are turnably secured to the side walls of the food storage compartment in order to allow the guide slots formed therein to be readily aligned to receive the sides of the border frame of the shelf, in spite of slight inaccuracies which may exist in the alignment of the brackets.

In order to obtain a quiet, smooth sliding action between the border frame of the shelf and the brackets, the supporting brackets are preferably formed of some non-metallic substance such, for example, as a resinous condensation product having a suitable filler, which material is obtainable on the market under the trade name "Textolite".

It will be understood that a plurality of vertically spaced sets of the shelf supporting brackets will be secured to the oppositely disposed side walls of the food storage compartment and that each set of brackets will be provided with a slideable shelf as described above.

In order to limit the outwardly sliding movement of the shelf 20 a stop member 30 is pivotally mounted to a bar 25 on opposite sides of the shelf 20 adjacent the sides 24 of the border frame. When the stop members 30 are pivoted into a horizontal position as shown in full lines in Fig. 2, the shelf may be slid only partially outwardly from the food storage compartment 13 through the door opening therein, due to the engagement between the outer hooked ends 31 of the stop members 30 embracing the side portions 24 of the border frame and the brackets 21 secured to the oppositely disposed side walls 19 of

the food storage compartment 13. In this partially withdrawn position tilting of the shelf is prevented by the projecting ends 32 of the brackets 21 disposed on each side of the guide slots 27 formed therein. The projecting ends 32 of the brackets 21 constitute abutments provided by the guide slots 27 formed therein to prevent tilting of the shelf 20. On the other hand, when the stop members 30 are pivoted into a vertical position as shown in dotted lines in Fig. 2, the shelf may be slid completely outwardly and removed from the food storage compartment 13 through the door opening therein.

In Fig. 3 I have shown two similar vertically spaced shelf supporting brackets 40 of modified construction secured to a side wall 19 of the food storage compartment 13. The upper bracket is one of an upper set of shelf supporting brackets and the lower bracket is one of a lower set of shelf supporting brackets. Each of the brackets 40 is provided with an upper and a lower guide slot 41 and 42, respectively, instead of a single guide slot such as is provided in the bracket 21 previously described, and is turnably secured to a side wall 19 of the food storage compartment 13 by a screw 43 threaded into an aperture 44 formed in the side wall 19. By employing two sets of these shelf supporting brackets of the modified construction described above, it is possible to obtain three different vertical spacings between two shelves supported by the two sets of brackets. In Fig. 3 these vertical spacings have been indicated as h_1 , h_2 , and h_3 .

While I have shown a particular embodiment of my invention in connection with a household type refrigerator, I do not desire my invention to be limited to the construction shown and described, and I intend in the appended claims to cover all modifications within the spirit and scope of my invention.

What I claim as new and desire to secure by Letters Patent of the United States is:

1. In a refrigerator cabinet having smooth interior rear and oppositely disposed side walls and a door opening in the front wall of said cabinet, a set of aligned shelf supporting brackets mounted on said side walls, said set of brackets including at least two brackets mounted on each of said side walls, each of said brackets having a guide slot formed therein, a shelf supported in said guide slots of said set of brackets, said shelf being slidable in said guide slots into and out of said cabinet through said door opening, said guide slots in said set of brackets providing abutments to prevent tilting of said shelf, and means including stop members pivotally mounted on opposite sides of said shelf for limiting the outward sliding movement of said shelf by engagement with said brackets.

2. In a refrigerator cabinet having smooth interior rear and oppositely disposed side walls and a door opening in the front wall of said cabinet, a set of aligned shelf supporting brackets mounted on said side walls, said set of brackets including at least two brackets mounted on each of said side walls, each of said brackets having a guide slot formed therein, a shelf including a border frame and a plurality of bars secured to said border frame, said border frame being supported in said guide slots of said set of brackets and slideable into and out of said cabinet through said door opening, said guide slots in said brackets providing abutments to prevent tilting of said shelf, and means including stop members pivotally mounted on opposite sides of said shelf and swingable into a position to engage said brackets for limiting the outward sliding movement of said shelf.

JAMES L. KNIGHT. 40
